CLOSURE FOR ACCESS OPENING IN PROPELLER SPINNER

Leo Avondoglio, Verona, N. J., assignor to Curtiss-Wright Corporation, a corporation of Delaware

Application June 19, 1952, Serial No. 294,341

2 Claims. (Cl. 220—35)

This invention relates to spinners for aircraft propellers and provides, on the one hand, a construction for a quickly detachable spinner and, on the other hand, a flush access door for a rotating or a non-rotating body.

In the design and construction of spinners for the propellers of aircraft a requirement is to make the spinner readily and quickly removable from the propeller assembly to enable servicing or detachment of the propeller from its shaft. Since the spinner is a streamlined body which must be free from protuberances, means to secure the spinner to the propeller must lie within the spinner body and yet must be accessible to enable simple assembly and disassembly. In the present invention, I provide a spinner construction wherein the entire spinner may be assembled or removed from a propeller as a unit by the attachment or detachment respectively, of a small number of securing bolts all located in the same plane and all readily accessible from the exterior of the spinner. Access openings are provided in the spinner so that the bolts may be reached, and I further provide closures for these access openings which normally provide a flush outer surface for the spinner and yet, which are readily movable to uncover the access openings.

Objects of the invention are to provide a quickly detachable spinner and to provide a simple closure for an access opening which is particularly suitable for a rotating body. A further object is to provide a closure for an access opening, which if left open inadvertently, will automatically close upon rotation of the body.

Further objects of the invention will become apparent in reading the annexed detailed description in connection with the drawings, in which similar reference characters denote similar parts and in which:

Fig. 1 is a longitudinal elevation, partly broken away, of a propeller and spinner assembly according to the invention.

Fig. 2 is a front elevation of the propeller and spinner assembly.

Fig. 3 is a fragmentary plan view of an access opening and a closure therefor.

Fig. 4 is an end elevation of the access opening and closure.

Fig. 5 is a section on the line 5—5 of Fig. 4.

Referring first to Figs. 1 and 2, I show a propeller hub 10 of any suitable type from which blade sockets 12 extend, and in which sockets blades 14 are secured. The hub 10 is mounted in a conventional manner, not shown, on a driving shaft. The structure upon which the propeller is mounted includes a rearward stationary streamlined cowling 16. Mounted upon the propeller is a spinner 18 which, as shown, embraces the propeller hub and provides a streamlined nose for the stationary cowling 16 and blends with the streamline of the stationary cowling at a spinner rearward edge 20. Since the spinner rotates with the propeller there is a gap 22 between the rear edge of the rotating spinner and the stationary cowling 16.

The spinner 18 is mounted upon two annular bulk-

2

heads 24 and 26 which are secured at 28 and 30 respectively to structural portions of the propeller hub. The forward bulkhead 24 comprises, at its outer edge, a resilient annular wear strip 32. The spinner includes an inwardly extending annular flange 34 and a substantial cylindrical annular member 36 secured thereto, the member 36, upon assembly of the spinner over the propeller hub, engaging the wear strip 32 so that the forward portion of the spinner is securely piloted upon the bulkhead 24.

The rearward portion of the removable spinner arrangement comprises an inwardly turned annular flange 38 which abuts an outer portion of the bulkhead 26. The flange 38 carries a plurality of bolts 40 secured thereto which bolts pass through appropriate holes in the outer portion of the bulkhead 26 so that nuts 42 may be spun on the bolts to secure the flange 38 to the bulkhead 26.

The outer rim of the bulkhead 26 is provided with rearwardly turned skirt portion 44 which forms a streamlined prolongation of the surface of the spinner 18 and which blends the spinner as mentioned previously, with the streamline of the stationary cowling 16. A plurality of access openings 46 are formed in the skirt 44 so that a mechanic may insert a wrench through the access openings to tighten or loosen the nuts 42. If the nuts 42 are removed, the entire spinner assembly including the parts 38, 36, 34, and 18 may be slid forwardly and removed from the propeller. After removal of the spinner, the propeller assembly may be serviced or removed in the conventional manner. Where the terms forward or rearward are used herein, they refer to a tractor propeller assembly. If the assembly is a pusher, forward means outboard and rearward means inboard.

A further feature of the spinner consists in providing slots 50 and openings 52 extending from a central location toward the rear of the spinner 18 to accommodate the projecting propeller blades 14. An insert 52 which blends with the surface of the spinner 18 is secured to the bulkhead 26 to complete the spinner form behind each propeller blade. Without the inserts 52, there would be gaps behind the propeller blades on account of the slots 50 which are necessary for assembly and disassembly of the spinner. Within the spinner and bordering each slot 50, a reinforcing channel member 56 is secured, this channel member serving to prevent bulging of the unsupported spinner portions when the spinner is rotating.

The access openings 46 unless closed in some manner, would leave a discontinuity in the streamlined spinner surface. To close these openings, I provide access doors which are shown in Figs. 3—5. Each access door consists of a closure plate 60 which is exteriorly formed to lie flush with the spinner skirt 44, the plate 60 being appropriately curved to conform to the curvature of the spinner. The plate 60 is secured to a supporting member 62 which comprises a bridge portion 64 underlying and secured to the plate 60 and underlying part of the skirt 44, inbent end portions 66 by which the member 62 is supported, and a shelf portion 68 which serves as a position limit stop for the closure assembly when in the open position. The portions 66 are provided with pivot openings 70 which are journaled on bolts 72 mounted in brackets 74 secured as by bolts or rivets 76 to the bulkhead 26. By this arrangement, the member 62 with the closure plate 60 may be swung as shown in Fig. 5 between a closing position (full lines) and an opening position (dotted lines). When in the closed position, the plate 60 is flush with the spinner surface. When in the open position, the plate 60 lies within the cowling and the portion 68 of the member 62 provides a shelf within the spinner. Opening of the member 62 is accomplished merely by pressing the fingers upon the rearward edge of the plate 60 and swinging it about the pivots

72 whereupon access may be had to the spinner holding nut 42. To provide small clearance for the plate 60 in the opening 46, the rearward edge of the latter is bevelled as shown. The shelf 68 provides a convenient means to catch the nut 42 after it is removed from its bolt to prevent its dropping into the large spinner hollow. When the spinner is assembled, the nuts 42 are applied through the access openings 46. The closures 60, 62 may be moved into the closing position by hand, by manipulation through the access openings, or they may be left open. If they are left open, they will be flung to a closed position upon rapid rotation of the spinner since centrifugal force urges them to the closed position on account of the off-set location of the center of gravity of the closure with respect to the pivots 72.

Means are provided to hold the closure elastically in either the open or closed positions. This means comprises tension springs 78, each having an end hooked to the portion 66 of a member 62, and an end to a tab 80 formed integrally with each bracket 74. The springs 78 are so located that their ends are off-set from the pivot axis 72 whereby the spring passes over the axis as a center to hold the closure either open or closed as clearly shown in Fig. 5. The springs 78 need not be stiff; their sole function is to hold the closure 62 open or closed during assembly or disassembly operations. During rotation of the spinner, the closures are held in flush position by the action of centrifugal force thereon as previously described.

Though one embodiment of the invention is shown, it is to be understood that the invention may be applied in various forms and in various environments. Changes may be made in the arrangements shown without departing from the spirit of the invention. Reference should be had to the appended claims for definition of the limits of the invention.

What is claimed is:

1. In a body including a wall having an access opening therein and including a portion extending inwardly from

the wall adjacent the edge of the opening, brackets within the body wall and secured to the body, a closure member for the access opening having inwardly disposed tabs cooperating with said brackets, pivot means between and engaging said tabs and brackets, said closure member being swingable on said pivot means to close the access opening in substantially flush relation to said wall, and to move inwardly and uncover the access opening whereupon said closure member lies inwardly of said wall and substantially normal thereto, and a shelf member secured to said closure member substantially normal thereto along an edge thereof remote from said extending portion, said shelf member being movable with said closure member so that when said closure member is flush with said wall, the shelf member projects substantially normally and inwardly from said wall, and so that when said closure member uncovers the access opening, said shelf engages said body extending portion and forms therewith and with said closure member a pocket within said body.

2. Structure according to claim 1 including an over-center spring means acting between said bracket and said closure member to hold said closure member in covering or uncovering position relative to the access opening.
